UNITED STATES PATENT OFFICE.

CHARLES E. JOHNSON, OF DENVER, COLORADO.

SPARK-PLUG.

1,029,613.

Specification of Letters Patent. Patented June 13, 1912.

Application filed January 27, 1911. Serial No. 805,059.

To all whom it may concern:

Be it known that I, CHARLES E. JOHNSON, a citizen of the United States of America, residing at the city and county of Denver, 5 and State of Colorado, have invented a new and useful Spark-Plug, of which the following is a specification.

My invention relates to improvements in spark plugs, and the objects of my invention 10 are: First—to provide a self-cleaning spark plug that an automobile chauffeur or a gasoline engine operator can manipulate in a few seconds to cause it to thoroughly clean itself by the expansive force of the explosions of the explosive mixtures of gasoline engines. Second—to provide a spark plug that is arranged to be manipulated to permit a quantity of the waste gases that result 15 from the explosions of explosive mixtures in gasoline engines to escape to the atmosphere. Third—to provide a spark plug provided with a valve controlled exhaust port leading from its spark gap end to the atmosphere and arranged to compel the exhaust 20 gases of the explosive charge of an engine to flow in contact with the spark gap, and clean them of sooty and gummy substance by its explosive force.

I attain these objects by the mechanism, 25 illustrated in the accompanying drawings, in which:

Figure 1 is a side elevation of the improved spark plug, showing the same in connection with a portion of an engine cylinder. Fig. 2 is a vertical, sectional view thereof, the outlet valve being closed. Fig. 3 is an elevation, partly in section, of the same, 35 showing the valve opened; and Fig. 4 is a horizontal, sectional view on the line 4—4 of Fig. 2.

Similar letters of reference refer to similar parts throughout the several views.

Referring to the drawings, the numeral 1 designates the porcelain, non-conductive portion 45 of the core of my improved self-cleaning spark plug. This non-conductive portion is in use in the spark plugs in common use and forms a co-operating element of my invention. This non-conductive portion 50 comprises a long body portion having a raised collar portion 2 intermediate of its ends and terminating in a conical pointed end portion at one end and a square end portion at its opposite end. A small aperture 55 3 is formed through the center of this por-

tion in which I insert a circuit wire 4 of the spark forming terminal; and while I may use for this purpose any suitable wire, I preferably make and arrange this circuit spark making wire as follows: A conductive wire of sufficient diameter at its outer end is provided with a threaded end 5, which I term a binding post, and on this binding post I thread a check nut 6. Below the threaded binding post portion the wire is drawn down smaller in diameter and is provided with a collar 7, adjacent to its lower end. The reduced portion of the wire is extended through the axial aperture of the porcelain portion with its larger threaded end portion against the square outer end 8 and the collar is then placed on the wire against the conical end and is secured thereby by solder or other suitable means. The washer nut 6, which is made of conductive material, then screwed onto the threaded end of the wire against the square end. The wire is thus secured to the porcelain of the core between its nut and collar. A terminal and conductive binding post nut 9 is also threaded to the threaded end of the wire and is adapted to clamp the terminal end of a current carrying wire against the conductive washer nut.

Upon the lower end portion of the porcelain part of the core I place a bushing sleeve 10, which is provided with an axial aperture of two different diameters, 11 and 12, the smaller one 11 of which fits loosely but snugly over the conical end portion of the porcelain adjacent to the inner end of the collar portion of the porcelain part of the core. The axial aperture of this bushing sleeve is made enough larger in diameter than the collar portion of the porcelain to extend loosely over it and is internally threaded, and conductive packing rings 13 and 14 of copper or other suitable material are placed around the opposite ends of the porcelain part of the core against the opposite ends of its collar portion, and the shoulder 15 in the bottom of the axial bore 12 of the bushing sleeve engages the packing ring 13 and is clamped against the end of the collar by a bushing plug 16, which is provided with an axial bore that fits loosely over the binding terminal end of the porcelain and is threaded to screw down into the bushing sleeve and bear against the packing ring 14 and clamp it against the adjacent 100 shoulder 15.

end of the collar portion of the porcelain. The bushing sleeve is thus tightly but removably clamped to the porcelain part.

To the lower end of the bushing sleeve I connect at one side of its diametrical center the opposite ends 17 of a bent conductive wire. This bent wire extends to the end of the circuit spark wire of the non-conductive portion of the core, and is provided with a small curved end portion, which is bent over at right angles to the lengths of the ends of the bent wire and is arranged to extend toward the end of the axial circuit spark wire of the porcelain, and close enough to it to leave a space or gap of sufficient size to permit a spark to form between the end of the circuit spark wire of the porcelain and the curved end of the bent wire. In Fig. 1 this bent wire and its loop is shown in side elevation.

The outer surface of the bushing sleeve is provided with a thread 19 from its end portion adjacent to the spark gap wires to near its opposite end, which is formed into a wrench receiving surfaces 20, and to this outer threaded surface of this bushing sleeve I thread a bushing 21, which I term the spark plug supporting bushing, which is adapted to be secured to the explosion ends of explosive mixture actuated engines in a position to permit the spark plug to ignite the explosive charge. This attaching bushing comprises a hexagon or other suitable wrench receiving end portion and a collar portion 23 at the inner end of the hexagon portion. Adjacent to the collar portion there is an outside threaded portion 24 of sufficiently smaller diameter to permit the adjacent side of the collar to act as a flange against the surface of the cylinder the bushing is screwed into. Below the outside threaded portion the bushing is provided with a reduced portion 25 that tapers to its end. This bushing is also provided with an axial threaded aperture 26 that extends into it from its hexagon end and is arranged and adapted to permit the bushing sleeve to screw into it, and from the bottom of the threaded aperture in the plug supporting bushing I form a conical tapering axial aperture 27 that extends to the end of this plug supporting bushing. The tapering inner end of this plug supporting bushing is made long enough to extend below the adjacent end of the core a short distance but terminates at a short distance above the spark gap loop of the spark wires, and is provided with a conical axial aperture that is made sufficiently larger in diameter than the adjacent taper, conical end of the non-conductive portion of the core to form an open space all around it and between it and the conical end of the plug supporting bushing, which I term the exhaust chamber. This exhaust chamber extends into the plug sup-

porting bushing from its terminal end to the lower end of the inner threaded aperture portion of the opposite end of the plug supporting bushing in which the bushing sleeve screws, and at the junction of this tapering chamber and the bottom of the threaded aperture a shoulder 28 is formed, and this shoulder is arranged and adapted to form a seat for the adjacent end of the bushing sleeve which is formed to bear against it. I preferably form a tapering or slightly downwardly beveled seat portion and provide the adjacent end of the bushing sleeve with a plug shaped taper end registering with the taper seat of the plug supporting bushing and arrange the bushing sleeve so that it will screw down against its seat and prevent any exhaust explosive gases from working by this seat, except when it is desired to clean the spark plug wires, as will be explained hereinafter. Adjacent to this seat of the plug supporting bushing I form through its shell one or more small apertures 30, preferably using and illustrating six of these, which I preferably arrange at equal distances apart in the squares of the hexagonal surface of the plug supporting bushing. These apertures form exhaust ports to the atmosphere for the gases of explosion when the bushing sleeve plug end is unscrewed and is thus lifted from its seat.

The plug shaped end of the bushing sleeve and the taper seat and exhaust gas aperture and the exhaust ports leading to the atmosphere through the plug bushing form a valve controlled exhaust passage for the gases of the explosions in the cylinder, and the entrance to this valve controlled exhaust passage is arranged around and in such close proximity to the spark gap of the electrodes that when the exhaust port is opened the expansive force of the explosion drives the gases in direct contact with the wires and cleans them of all sooty, sticky, gummy and other material that they collect and which causes them to frequently miss sparking and finally become inoperative to ignite an explosive charge within the cylinder.

The operation is as follows: The spark plug supporting bushing is threaded secured to the explosive end of a gasoline engine, as shown in Fig. 2, and the core comprising the bushing sleeve and the porcelain center are inserted in it, the bushing sleeve being threaded into it, with its valve end down tight against the valve seat 28 of the plug supporting bushing, thus closing the exhaust passage from the interior of the explosive end of the cylinder to the atmosphere. An electric circuit wire is then connected to the binding post by placing its end around the post between the binding post's nut 9 and the fixed washer nut 6 and tightening the binding post's nut against the end of the wire. The electric current then flows

through the central electrode and sparks across the gap between the end of this wire and the loop of the loop wire, and flows through the bushings and casing of the engine to any suitable electrically arranged spark timing device or mechanism that it is desired to use on the engine and which I do not illustrate, as there are a number of different spark timing devices in common use, and it does not form a part of my present invention. The chauffeur or operator of an engine or of an automobile engine provided with my self-cleaning spark plug when he desires to clean the plug applies a wrench to the wrench receiving surfaces of the bushing sleeve and unscrews it out of the plug supporting bushing far enough to lift its valve end from the seat and at the same time uncovering the aperture 27 leading from this valve seat to the atmosphere, when the gases that result from the explosion are forced at each explosion with great force against the spark gap of the wire and into and through the conical exhaust chamber 25 and passage by and between the valve seat and the valve end of the bushing sleeve into and through the exhaust apertures 30 to the atmosphere, cleaning the wires of any and all accumulation of material detrimental to their continuous and positive sparking function. The operator having blown out and cleaned the wires and adjoining end of the spark plug screws the bushing sleeve down until its valve end engages its seat and closes the exhaust port and allows the engine to run until he again desires to clean the sparking wires, when he again opens and closes the bushing valve, and he can instantly at any time or place clean the spark wires by unscrewing the bushing sleeve enough to open, thus opening for a few seconds its valve without stopping the engine.

My invention contemplates the forming of a gas exhaust passageway to direct the gases of the explosion of explosive mixtures to flow in direct contact with the spark making wires and its passage from the explosive cylinder to the atmosphere to clean them of any and all material that interferes with the flow of the electric current through them in such an operative manner as to insure that they will be in operative spark producing order; and, while I have illustrated and described the preferred arrangement of my invention, I do not wish to be limited to the construction and arrangement shown, as many changes might be made without departing from my invention.

Having described my invention, what I claim as new and desire to secure by Letters Patent is:

1. A spark-plug comprising a core having a non-conductive portion provided with one terminal, a bushing provided with a thread-

ed aperture at its outer end, its inner end 65 being spaced from said non-conductive portion to form an exhaust-chamber and having a valve-seat portion between its threaded end and exhaust-chamber portion and a spark-gap wire attached to said core and extending through said chamber, said bushing having one or more gas-exhaust apertures therethrough located outside said valve-seat, 70 said core having a threaded member engaging the outer threaded end of the bushing, 75 and a valve formed by said core arranged to cooperate with said valve seat to close the outer end of said exhaust-chamber.

2. A spark-plug comprising a core having a non-conductive portion provided with one 80 terminal, a bushing provided with a threaded aperture at its outer end, its inner end being spaced from said non-conductive portion to form an exhaust-chamber and having a valve-seat portion between its threaded 85 end and exhaust-chamber portion and a spark-gap wire attached to said core and extending through said chamber, said bushing having one or more gas-exhaust apertures therethrough located outside said valve-seat, 90 said core having a threaded member engaging the outer threaded end of the bushing arranged to carry said non-conductive portion and adapted to cooperate at its inner end with said valve-seat to close the outer 95 end of said exhaust-chamber.

3. A spark-plug comprising a core having a non-conductive portion provided with one terminal, a bushing provided with a threaded aperture at its outer end, its inner end 100 being spaced from said non-conductive portion to form an exhaust-chamber and having a valve-seat portion between its threaded end and exhaust-chamber portion and a spark-gap wire attached to said core and extending through said chamber, said bushing having one or more gas-exhaust apertures therethrough located outside said valve-seat, 105 said core having a threaded member engaging the outer threaded end of the bushing, 110 an annular plug movable within said threaded member and arranged to maintain the non-conductive portion in carrying engagement therewith; and said threaded member adapted to cooperate at its inner end with 115 said valve-seat to close the outer end of said exhaust-chamber.

4. A spark-plug comprising a core having a non-conductive portion provided with one terminal, a bushing provided with a threaded aperture at its outer end, its inner end being spaced from said non-conductive portion to form an exhaust-chamber and having a valve-seat portion and a spark-gap wire attached to said core and extending 120 through said chamber, said bushing having one or more gas-exhaust apertures therethrough located outside said valve-seat, 125 said

core having a threaded member engaging the outer threaded end of the bushing, a collar on the non-conducting portion of said core, an annular plug movable within said threaded member and against the collar portion to maintain said non-conductive portion in carrying engagement with the threaded member, and said threaded member adapted to coöperate at its inner end

with said valve-seat to close the outer end 10 of said exhaust-chamber.

In testimony whereof I affix my signature in presence of two witnesses.

CHARLES E. JOHNSON.
